UNITED STATES PATENT OFFICE.

CHARLES F. HUMMEL, OF ILION, NEW YORK.

DIE-CASTING MACHINE.

Application filed March 8, 1924. Serial No. 697,774.

To all whom it may concern:

Be it known that I, CHARLES F. HUMMEL, a citizen of the United States of America, residing at Ilion, in the county of Herkimer 5 and State of New York, have invented certain new and useful Improvements in Die-Casting Machines, of which the following is a specification.

My invention relates to casting apparatus 10 and more particularly to the mold or die supports thereof.

An important object of the invention is the provision of a device of the above mentioned character with means to lock the 15 mold or die support in its downward position so that the support can not be moved unless deliberately unlocked, thereby insuring safety to the operator.

Another object of the invention is to provide a device of this character which will combine the support lifting and unlocking operations, whereby economy of time and 20 energy will be effected.

A further object of the invention is the provision of a device of this character which will be simple in construction and operation, strong and durable.

Other objects and advantages of the invention will be apparent during the course 30 of the following description.

In the accompanying drawings which form a part of this specification and in which like numerals are employed to designate like parts throughout the same:

35 Figure 1 is an elevation of a die casting machine embodying my invention.

Figure 2 is a plan view of the same, parts being broken away.

40 Figure 3 is a vertical sectional view taken on the line 3—3 of Figure 2, and looking in the direction of the arrows.

Figure 4 is a similar view, showing the mold or die support in its unlocked and raised position.

45 Figure 5 is a side elevation of the mold support and its locking and operating mechanism.

Figure 6 is a similar view showing the mold or die support in its raised position.

50 Figure 7 is a perspective view of the operating and locking mechanism.

Figure 8 is a detail perspective view of the operating shaft and sleeve, and

55 Figure 9 is a detail sectional view taken on the line 9—9 of Figure 2.

In the drawings wherein for the purpose of illustration is shown a preferred embodiment of my invention, the numeral 10 designates a die casting machine of the usual construction, and although shown as a center gated type, my invention is not limited to any type or construction of casting machine. This machine 10 is provided with a removable cover or top 11 of the usual formation which has the usual nozzle 12 arranged substantially centrally thereof. Upstanding lugs 13 are arranged at the edges of the cover 11, in which the rotatable sleeve 14 is journaled, with one of its ends 15 extending beyond the lug a substantial distance. Rotatably mounted within the sleeve 14 is a shaft 16 which is provided with spaced pinions 17 which are spaced from the ends of the shaft. Openings 18 are formed in the sleeve 14 to correspond to the pinions 17, and the mold or die support or base 19 is rigidly mounted on the sleeve 14 by means of the lugs 20, which are also provided with openings 21 which correspond to the openings 22 in the lugs 23 carried by the opposite end of the support 19. Arranged within the openings 21 and 22 are slideable locking rods or latches 24 having their ends turned up to form stops 25. These rods or latches 24 are provided with racks 26 which mesh 80 with the pinions 17. Upright lugs 27 are arranged on the cover 11 and have openings 28 to receive the ends of the rods or latches 24 and to act as keepers. These lugs are provided with bevelled guides 29 to guide the rods 24, and the ends of the rods are 85 also preferably bevelled.

A lever 30 is mounted on the projecting end 15 of the sleeve 14 to turn therewith. In the form shown in the drawing a transverse slot 31 receives the lug 32 of the lever 30 and a small amount of "play" is allowed between the lever and the sleeve. Rigidly attached to the end of the shaft 16 is a manually operated lever or 100 handle 33 which has an extension 34 provided with a segmental slot 35. This slot is adapted to receive the pin 36 which is rigidly mounted in the lever 30. A coil spring 37 has one of its ends connected to the outer end of this pin 36, and the other end of the spring is connected to some part 105 of the frame work of the casting machine 10.

The cover 11 may also be provided with 110

guides 39 arranged in alignment with the locking rods or latches. The support 19 has a central opening 38 adapted to align with the nozzle 12 when the support is in its lowered position, and the mold is supported on the base 19 and over the opening 38 and nozzle 12.

In operation, the support or base 19 is normally in its lowered position with the locking rods or latches in their locking position with their ends in the openings 28. When it is desired to raise the die support 19, the handle or lever 33 is manually raised. This will rotate the shaft 16 and the pinions 17 will operate the latches and withdraw them from the openings 28, thereby unlocking the support 19. During this operation the sleeve 14 will remain stationary, due to the slot 35. When the end of the slot 35 is reached, continued raising of the lever of handle 33 will raise the lever 30, through the pin 36, and when the end of the slot 31 is reached, by the lug 32, further movement of the handle will rotate the sleeve 14. This rotation of the sleeve 14 will cause the support 19 to swing upwardly about the sleeve as a pivot, which will remove the support from the nozzle 12. The upward movement of the lever 30 is under the tension of the spring 37 which will serve to return the support 19 to its downward position when the handle 33 is released. Downward movement of the handle will rotate the shaft 16 and pinions 17 and return the latches to their locking position within the openings 28.

It will therefore be seen that the unlocking and raising of the support is accomplished by a single movement of the handle or lever 33 and that the support will not be unlocked unless it is intended to be raised.

It is to be understood that the form of my invention herewith shown and described is to be taken as a preferred embodiment of the same and that various changes in the shape, size and arrangement of parts may be resorted to without departing from the spirit of my invention or the scope of the subjoined claims.

Having described my invention what I claim and desire to protect by Letters Patent is:

1. In a casting machine, a mold support, means to lock the mold support in its lowered position and means to unlock and raise the support in a single operation.

2. In a casting machine, a support, means to lock the support in its lowered position, an operating lever, and means whereby when the operating lever is moved, the support will be unlocked and when the lever is moved further the support will be moved to its raised position.

3. In a casting machine, a support, a latch carried by said support and adapted

to enter a keeper, and means to withdraw the latch from the keeper and raise the support, in a single operation.

4. In a casting machine, a rotatable sleeve, a mold support rigidly mounted thereon and adapted to be locked in its lowered position, a shaft rotatably mounted in said sleeve and means operative by said shaft to unlock the mold support and swing it to its raised position. 70

5. In a casting machine, a rotatable sleeve, a mold support rigidly mounted thereon and adapted to be locked in its lowered position, a shaft rotatably mounted in the sleeve, means to rotate the shaft independently of the sleeve to unlock the mold support, and means whereby the sleeve will be rotated by the shaft to swing the mold support to its raised position. 80

6. In a casting machine, a rotatable sleeve, a die base rigidly mounted thereon, and adapted to be locked in its lowered position, a shaft rotatably mounted within said sleeve, a lever carried by the shaft, means whereby movement of the lever will rotate the shaft to unlock the die base, and means whereby further movement of the lever will rotate the sleeve to swing the die base to its raised position. 90

7. In a casting machine, a rotatable sleeve, a support rigidly mounted thereon, and adapted to be locked in its lowered position, a shaft rotatably mounted within said sleeve, a lever carried by the sleeve and a second lever carried by the shaft and having a segmental slot, said first named lever having an extension to engage in said slot. 95

8. In a casting machine, a rotatable sleeve, a support rigidly mounted thereon, a shaft rotatably mounted in said sleeve, a latch carried by the support, a keeper for said latch, a rack carried by said latch, a pinion carried by the shaft and adapted to mesh with said ratchet, a lever carried by the sleeve, a lever carried by the shaft and having a segmental slot, and an extension carried by said first named lever to engage in said slot. 105

9. In a casting machine, a rotatable sleeve, a support rigidly mounted thereon, a shaft rotatably mounted within said sleeve, latches carried by the support, keepers to receive said latches, racks carried by said latches, pinions carried by the shaft to engage the racks, a lever carried by the sleeve, a lever carried by the shaft and having a segmental slot, a lateral extension carried by said first named lever to engage in the segmental slot, and tensioning means attached to the lateral extension. 110

10. In a casting machine, a rotatable sleeve having spaced openings, a support rigidly mounted thereon, latches carried by the support to lock it in its lowered position, said latches being provided with teeth, 120

a rotatable shaft mounted within said sleeve, pinions carried by said shaft adjacent the openings in the sleeve, said pinions being adapted to mesh with the teeth in the 5 latches, a lever attached to the sleeve, said sleeve having a slot, a lug carried by the lever to engage within the slot, a lever carried by the shaft and having a segmental

slot therein, a pin carried by the first named lever to engage within the slot, and a coil 10 spring attached to said pin to tension the same.

In testimony whereof I affix my signature.

CHARLES F. HUMMEL.
